UNITED STATES PATENT OFFICE.

CHARLES W. STAMBAUGH AND VALENTINE L. NEY, OF CANTON, OHIO.

WHEELBARROW.

SPECIFICATION forming part of Letters Patent No. 408,994, dated August 13, 1889.

Application filed February 14, 1889. Serial No. 299,857. (No model.)

To all whom it may concern:

Be it known that we, CHARLES W. STAMBAUGH and VALENTINE L. NEY, citizens of the United States, residing at Canton, in the county of Stark and State of Ohio, have invented certain new and useful Improvements in Wheelbarrows; and we do hereby declare that the following is a full, clear, and exact description of the same, reference being had

5 to the annexed drawings, making a part of this specification, and to the letters and figures of reference marked thereon, in which—

Figure 1 is an isometrical view. Fig. 2 is a side view showing the wheel located at the front end of the barrow. Fig. 3 is a side view showing the wheel located under the box. Fig. 4 is a view of the sheet properly cut to form a box. Fig. 5 is a top view of the front or forward end of one of the bars, showing the plate properly located thereon. Fig. 6 is a sectional view of the front or forward portion of one of the bars, showing the different parts belonging thereto properly attached. Figs. 7 are detached views of one of the sockets and its retaining-bar. Fig. 8 is a detached view of one of the pins. designed and calculated to lock the wheel.

The present invention has relation to wheelbarrows; and it consists in the different parts and combination of parts hereinafter described, and particularly pointed out in the claims.

Similar letters of reference indicate corresponding parts in all the figures of the drawings.

In the accompanying drawings, A represents the side bars and handles, which are constructed in the ordinary manner, reference being had to properly attaching the different parts thereto. These bars and handles are held in the desired position by means of the usual cross-bars and braces. The legs B are located substantially as illustrated, and are properly attached and braced to the bars and handles A. To the front or forward ends of the bars A are securely attached the front ends of the inclined and curved bars C. The opposite ends of these inclined and curved bars C are securely attached to the block or 45 arm D. The front or forward ends of the inclined bars C are bent or curved, as illus-

trated in Figs. 2 and 3, and are so formed for the purpose of providing suitable bearings for the axle a when it is desired to lock or stay the wheel in the position shown in Figs. 55 1 and 2. The rear or opposite ends of the inclined and curved bars C are bent so as to form bearings for the axle a when the wheel is located as illustrated in Fig. 3.

For the purpose of permanently holding the 60 wheel E in the position shown in Figs. 1 and 2, and thereby forming an ordinary or common wheelbarrow, the pins b are provided, and are so adjusted in the bars A that when they are pressed or forced downward they will 65 pass directly back of the axle a. For the purpose of securely holding the pins b in the position shown in Figs. 2 and 3, the feather or extension c is provided, which passes through the slot d in the plate d' when said 70 pin is turned partially around, thereby securely locking the pin in the position shown in Figs. 2 and 3. For the purpose of preventing the pins b from becoming detached, the rib e' is provided. In use the head of 75 the pin b is passed through the rounded portion of the slot d in the plate d', after which said plate is securely attached, as illustrated in the drawings.

When it is desired to permanently hold the 80 wheel E in the position shown in Fig. 3, the disk or plate F is rotated on the pin or rivet e, thereby bringing the retaining bar or pin f directly in front of the axle a, and extending the end of the retaining-bar f through the 85 aperture g. It will be seen that by this peculiar arrangement the wheel E can be permanently held in either of the positions shown in Figs. 2 and 3.

When it is desired to have the wheel E act 90 as a roller in passing from one end of the inclined bars C to the opposite ends, the pins b are elevated until the axle a is freed, and the pins placed in the position shown in Fig. 3. The plate F is rotated backward, thereby 95 throwing the retaining-bar f back out of the way of the axle a.

It will be seen by our peculiar arrangement that when the wheelbarrow proper is loaded and pushed forward, the wheel E will 100 strike or bear against the bottom or under side of the box G and act as a roller until

the wheel reaches the rear sockets, at which time the wheel E is freed from the box G and is free to rotate at a given or fixed point upon its axle a. When the wheel E again reaches 5 the front or forward ends of the inclined and curved bars C, the axle a stops and rotates against the pin b. It will be seen that by providing the wheel E and adjusting the same so as to act as a roller until it has assumed 10 a position substantially directly under the load, the weight of the load is removed to a great extent from the arms of the operator, thereby providing a wheelbarrow which is easily operated and capable of conveying very heavy loads with ease. It will also be seen that the wheelbarrow can be easily dumped of its load, as the wheel is in position to receive the greater amount of the weight.

In case it is desired to use the wheelbarrow 15 in the ordinary form, the wheel E can be easily placed in the position shown in Fig. 1.

For the purpose of providing a means for rotating or turning the disk or plate F, the lugs h are provided.

20 The arms or blocks D are securely attached to the handles or bars A by means of suitable cross-bars or their equivalents, and to the bottom or lower ends of which are attached in any convenient manner the inclined bars C.

25 The box G is formed of a single sheet of metal, which is cut or notched as shown at x, Fig. 4, and the edges lapped over each other and riveted. It will be understood that the box G is to be securely attached to the bars or handles A in any convenient and 30 well-known manner.

Having fully described our invention, what

we claim as new, and desire to secure by Letters Patent, is—

1. In a wheelbarrow, the wheel E, adapted 40 to move under and receive the weight of the load independent of its axle, substantially as and for the purpose set forth.

2. The combination of the bars or handles A, the inclined curved bars C, bent to hold 45 the axle a at either end of said bars, and the wheel E, substantially as and for the purpose set forth.

3. The combination of the wheel E and its axle a, the inclined bars C, and means for 50 locking the wheel E at either end of the inclined bars C, substantially as and for the purpose set forth.

4. The combination of the plate or disk F, provided with the lugs h, the retaining-bar f 55 and the inclined bars C, and the wheel E, substantially as and for the purpose set forth.

5. The combination of the bars or handles A, the pins b, provided with the feathers c and the ribs c', the inclined bars C, and the 60 wheel E, substantially as and for the purpose set forth.

6. The combination of the inclined bars C and means for locking the wheel E at either end of the inclined bars C, substantially as 65 and for the purpose set forth.

In testimony that we claim the above we have hereunto subscribed our names in the presence of two witnesses.

CHARLES W. STAMBAUGH.
VALENTINE L. NEY.
